US00D817385S

(12) **United States Design Patent** (10) **Patent No.:** **US D817,385 S**
(45) **Date of Patent:** **** May 8, 2018**

(54) **HUMBUCKING PICKUP**

(71) Applicants: **Fender Musical Instruments Corporation**, Scottsdale, AZ (US); **E.L.V.H., Inc.**, Los Angeles, CA (US)

(72) Inventors: **Timothy P. Shaw**, Hendersonville, TN (US); **Edward Lodewijk Van Halen**, Los Angeles, CA (US); **Matthew Jonathon Bruck**, Studio City, CA (US); **Joshua D. Hurst**, Nashville, TN (US)

(73) Assignees: **Fender Musical Instruments Corporation**, Scottsdale, AZ (US); **E.L.V.H., Inc.**, Los Angeles, CA (US)

(**) Term: **15 Years**

(21) Appl. No.: **29/580,771**

(22) Filed: **Oct. 12, 2016**

(51) LOC (11) Cl. **17-03**

(52) U.S. Cl. **D17/20**
USPC ....
